Primary Examiner — Marie D. Fast Horse*Assistant Examiner* — Jennifer Sierra Yosinski(74) *Attorney, Agent, or Firm* — Honigman LLP; Eric J. Sosenko; Jonathan P. O'Brien(57) **CLAIM**

The ornamental design for a shower caddy, as shown and described.

DESCRIPTION

FIG. 1 is a perspective view of a shower caddy showing my new design;

FIG. 2 is a front elevational view of the shower caddy seen in FIG. 1;

FIG. 3 is a rear elevational view of the shower caddy seen in FIG. 1;

FIG. 4 is a right side elevational view of the shower caddy seen in FIG. 1, the left side elevational view being a mirror image thereof;

FIG. 5 is a top plan view of the shower caddy seen in FIG. 1; and,

FIG. 6 is a bottom plan view of the shower caddy seen in FIG. 1.

In the drawings, the broken lines depict portions of the shower caddy that form no part of the claimed design. Shade lines, having a combination of long and short lines in the drawings, show contour and not surface ornamentation.
